POLICE LOCK

Melvyn A. Gervis, Haworth, and Eugene Taras Wozny,
Harrington Park, N.J., and Nicholas Giardina, Mount
Vernon, N.Y., assignors to Magic Eye Associates, Inc.,
New York, N.Y., a corporation of New York

Filed Jan. 16, 1969, Ser. No. 15,377

Term of patent 14 years

Int. Cl. D8—03

U.S. Cl. D8—109

FIG. 1

FIG. 2

FIG. 1 is a three-quarter top perspective view of a police lock, showing my new design; and

FIG. 2 is a three-quarter bottom perspective view thereof.

The dominant portions of the design are shown in solid lines.

We claim:

The ornamental design for a police lock, as shown and described.
